UNITED STATES PATENT OFFICE.

ANDRÉS GARCIA, OF BROOKLYN, NEW YORK.

PROPELLER.

Application filed March 27, 1924, Serial No. 702,291. Renewed December 7, 1925.

To all whom it may concern:

Be it known that I, ANDRÉS GARCIA, citizen of Spain, residing at Brooklyn, in the county of Kings and State of New York, have invented certain new and useful Improvements in Propellers, of which the following is a specification.

This invention relates to boat propellers of the helical or screw type, the invention having more particular reference to a propeller arranged to present a variable surface, whereby the propeller can be more suitably adjusted to the boat and engine to which it is applied, the invention having for an object the provision of a novel propeller of this type which can be readily adjusted to vary its effective surface.

For further comprehension of the invention, and of the objects and advantages thereof, reference will be had to the following description and accompanying drawing, and to the appended claims in which the various novel features of the invention are more particularly set forth.

Fig. 1 of the drawing is a sectional view showing a two-bladed propeller with the invention applied thereto, this view being taken transversely of the propeller axis and along the line 1—1 of Fig. 2.

Fig. 2 is an axial sectional view of this propeller.

Figs. 3 and 4 are face views of three and four bladed propellers respectively having the invention applied thereto.

Fig. 5 is a side view of Fig. 3.

Referring now to the drawing, the reference numeral 10 indicates the hub of the propeller, and the reference numeral 11 the shaft on which the propeller is mounted. The blades of the propeller are shown at 12 and are formed integral with the hub. Formed in the outer end of each of these blades is a recess or slot 14 which is entered radially into the blade from the outer edge thereof. These slots or recesses 14 are of a length nearly equal to the length of the blades, circumferentially considered.

Freely mounted in each of the slots or recesses 14 is a leaf or plate 16 which is arranged for radial movement or adjustment in said recesses, and which may be adjusted to project 6 different distances beyond the circumferential edge of the blade to increase or decrease the area of the latter when desired. Fixed to the inner edge of each leaf

16, midway between the ends of the latter, is a rod 17 which extends radially inward through the blade and through the hub, the inner ends of these rods having enlarged heads 18 which engage cam projections on the shaft 11 the heads 18 being held in engagement with these cam projections by means of the coiled expansion springs 20 which surround the said rods and bear on the heads, these expansion springs being accommodated in the enlarged inner ends 21 of the passages in the blades through which the rods extend. It is to be understood of course that these springs 20 will be of sufficient strength to resist the centrifugal force developed when the propeller is rotating. To accommodate the cam projections 19 the hub 10 is formed with an annular recess 23. The propeller may be secured to the shaft 11 by suitable means permitting of angular adjustment of the propeller on the shaft, a set screw 25 being here shown as passed through the hub of the propeller and bearing on the shaft.

As will be apparent, by adjusting the propeller angularly on the shaft, the degree of projection of the leaves 16 beyond the bodies of the blades, may be varied and in consequence the effective surface or area of the propeller is varied. While I have indicated the propeller as being formed of a single casting, it will be understood that in manufacturing the propeller it will be conveniently formed in two halves which are later secured together.

In Figs. 3 and 4 I have shown the invention applied respectively to three and four bladed propellers, it being understood that each blade is provided, in addition to the leaf 16 which the drawing shows, with a rod 17 and adjusting cam 19.

While I have illustrated and described a preferred embodiment of my invention it is to be understood that I do not limit myself to the precise construction herein shown, and that various changes and modifications might be made therein without departing from the spirit and scope of the invention as defined in the appended claims.

Having thus described my invention what I claim as new and desire to protect by Letters Patent of the United States is as follows:

1. A propeller comprising a hub, and blades, radially adjustable leaves in said

blades, a shaft on which said propeller is mounted, and cam elements on said shaft for retaining said leaves in radially adjusted positions.

5. 2. In combination, a propeller comprising a hub and blades, radially adjustable leaves in said blades, a shaft on which said propeller is mounted, cam projections on said

shafts, and rods connected to said leaves and extending radially inward through the said 10 blades and hub to engage the said cam projections.

In testimony whereof I have affixed my signature.

ANDRÉS GARCIA.
